UNITED STATES PATENT OFFICE.

COSIMO CANDIDO, OF NEW YORK, N. Y.

VEHICLE-FENDER.

1,368,387.

Specification of Letters Patent. Patented Feb. 15, 1921.

Application filed December 1, 1920. Serial No. 427,570.

To all whom it may concern:

Be it known that I, COSIMO CANDIDO, a citizen of the United States, residing at Bronx, New York city, in the county of 5 Bronx and State of New York, have invented new and useful Improvements in Vehicle-Fenders, of which the following is a specification.

This invention relates to vehicle fenders, 10 and it comprises a pair of pivoted, curved arms adapted to form a grapple, means for automatically closing said arms, means for normally maintaining said arms in open, operative position, said means comprising a 15 member adapted to be removably arranged between said arms, and means for displacing said member to permit operation of said device, said means comprising a trigger engaging said member and normally maintaining 20 it in position, and operating means for said trigger comprising a flexible element having a portion thereof arranged in front of the vehicle, whereby the trigger is released when an object or person is struck 25 by the vehicle and the arms closed.

In the present invention, I have provided a fender for automobiles or other vehicles in which a pair of curved arms are arranged on the front of the vehicle, and springs are 30 provided which tend to normally close the arms. The arms are held in open position by means of suitable trigger actuated mechanism whereby they will automatically close when an object or person is hit by the machine, and the object or person will be caught 35 between the arms and prevented from passing under the wheels of the machine. The arms may be provided with suitable cushioning means whereby the shock of the collision 40 is lessened and serious injury avoided.

The invention further comprises novel operating means including a plate adapted to be arranged between the arms when the arms are in open position, and a trigger engaging 45 a portion of said plate to hold it in position. When the trigger is operated and the plate is free to move forward, the arms are closed by the pressure of springs bearing against them. The trigger is operated by means of 50 a flexible cable or cord arranged over the trigger, and extending in front of the vehicle whereby the pressure exerted on the cable by a person being hit will release the trigger and operate the fender.

55 In the accompanying drawings, I have

shown an advantageous embodiment of this invention. In the showing,

Figure I is a plan view of the device showing it in open or operative position.

Fig. II is a similar view showing the device closed.

Fig. III is a side elevation of the fender in closed position.

Fig. IV is an enlarged sectional view on line 4—4 of Fig. I.

Fig. V is a detailed perspective view of the locking plate; and

Fig. VI is a detail view showing the position of curved arms in closed position.

Referring to the drawings, the reference 70 numeral 1 designates a rigid stationary member which may be secured to the front of a motor vehicle (not shown) in any suitable manner. A pair of arms 2 are arranged near each end of the supporting member 75 and extend outwardly therefrom. These arms receive a supporting member or guard 3 having its ends curved or extended outwardly as at 4. A U-shaped member 5 is secured to the stationary member and arranged intermediate its ends. A plurality of bolts 6 are arranged in openings in the stationary member the bolts being retained therein by nuts 7.

80 Springs 8 are arranged on these bolts and 85 positioned between the stationary member, and a movable member 9 slidably mounted on the bolts, the member 9 being normally held in outer position by the springs. The outward movement is limited by the bolt 90 heads 10 which are too large to pass through the openings therein. As shown the ends of the spring may be received in cups 11 arranged on the bolts.

95 A pair of curved fender arms 12 are pivotally supported on the outer end of the U-shaped member 5. The inner ends of the fender arms are flattened as at 13 and are adapted to be received between the arms of the U-shaped member (see Fig. IV), a pivot 100 pin 14 passing through the ends of the arms and being secured to the U-shaped member. The flattened portions of the fender arms are adapted to pass through an aperture 15 in the slidable member 9 (see Fig. VI) and 105 the pressure of springs 8 is adapted to force the slidable member outwardly beyond the pivot 14 and close the fender arms (see Figs. II and VI).

110 The fender arms are held in open position

by means of a butterfly member comprising a main portion 16 and a pair of curved arms 17 which are adapted to rest against the fender arms as shown and hold the 5 slideable member 9 in set position against the tension of the springs. This butterfly member is provided with a trigger engaging portion 18 which engages the hammer 19 of a gun trigger 20 to hold the fender in 10 operative position. The trigger may be mounted in a suitable bracket 21 secured to the frame of the machine.

The trigger is operated by means of a flexible element, such as a rope or cable 22 15 which passes over the finger piece 23 and through a guide ring 24. Eye bolts 25 may be arranged on the frame of the machine to serve as guides for the flexible element, the ends of the flexible elements being secured 20 to links 26 pivoted in rings 27 on the arms 4. The opposite ends of the links are connected by a coil spring 28 extending across the front of the fender arms. The fender arms may be provided with cushioning 25 members 29.

In operation, the device is mounted on the front of a vehicle and the parts set in the position shown in Fig. I, the springs 8 being under tension, and the fender arms 12 being 30 open. The parts are retained in this position by the butterfly member, the curved arms 17 of said member contacting with the fender arms to retain them open. The butterfly member is held in position by engagement of trigger portion 18 and hammer 19. 35 When an object gets in front of the vehicle and is struck, the coil spring 28 moves inwardly and the ends of the pivoted links 26 to which the spring is attached are moved 40 toward each other. The opposite ends of the links are moved outwardly applying sufficient pressure to the flexible element 22 to operate the finger piece 23 of the trigger and release the butterfly member. The 45 springs 8 then force the slideable member 9 outwardly to the position shown in Figs. II and VI and draw the arms 12 together.

The butterfly member may be secured to a portion of the fender or vehicle by a chain 50 or cord so that it will not be lost when it is released. The cushioning members 29 break the force of the blow if a person is struck, and the closing of arms 12 prevent the person from passing under the wheels of the 55 vehicle, thus avoiding serious injury.

What I claim is:—

1. A vehicle fender comprising a pair of pivoted arms, a slideable member to close

said arms, springs arranged to exert a pressure on said slideable member, a plate engaging said arms to retain them in open position, and means for automatically releasing said plate when an object is struck by the vehicle. 60

2. A vehicle fender comprising a pair of pivoted arms, a slideable member to close said arms, springs arranged to exert a pressure on said slideable member, a plate engaging said arms to retain them in open position, and means for automatically releasing 70 said plate when an object is struck by the vehicle, said slideable member being adapted to close said arms, a plate engaging said arms to normally retain them in open position, and means for releasing said plate 75 when an object is struck by the vehicle.

3. A vehicle fender comprising a pair of pivoted arms, a slideable member to close said arms, springs arranged to exert a pressure on said slideable member, a plate engaging said arms to retain them in open position, said plate being provided with a trigger engaging portion, a trigger mounted on a suitable support and adapted to engage said trigger engaging portion, and means for operating said trigger when an object is struck 85 by the vehicle. 80

4. A vehicle fender comprising a pair of pivoted arms, a slideable member to close said arms, springs arranged to exert a pressure on said slideable member, a plate engaging said arms to retain them in open position, said plate being provided with a trigger engaging portion, a trigger mounted on a suitable support and adapted to engage 90 said trigger engaging portion, a flexible element engaging said trigger, and means for supplying pressure to said flexible element when an object is struck by the vehicle. 95

5. A vehicle fender comprising a pair of pivoted arms, a slideable member to close said arms, springs arranged to exert a pressure on said slideable member, a plate engaging said arms to retain them in open position, 105 said plate being provided with a trigger engaging portion, a trigger mounted on a suitable support and adapted to engage said trigger engaging portion, a flexible element engaging said trigger, a pivoted link to 110 which said flexible element is secured, and means for moving said link on its pivot when an object is struck by the vehicle.

In testimony whereof I affix my signature.

COSIMO CANDIDO.
